The ornamental design for a cutlery basket, as shown and described.

DESCRIPTION

FIG. 1 is a front perspective view of a cutlery basket showing our new ornamental design;

FIG. 2 is a front view thereof;

FIG. 3 is a rear view thereof;

FIG. 4 is a top view thereof;

FIG. 5 is a bottom view thereof;

FIG. 6 is a right side view thereof with the left side view thereof being a mirror image thereof; and,

FIG. 7 is a bottom perspective view thereof.

The broken lines of the cutlery basket show surrounding structure or environment and do not form part of the claimed design.
